UNITED STATES PATENT OFFICE.

JOSEPH E. SCHUMACHER, OF LOS ANGELES, CALIFORNIA.

COLLAPSIBLE AND EXPANSIBLE SHELTER.

1,375,420.

Specification of Letters Patent. Patented Apr. 19, 1921.

Application filed June 20, 1917. Serial No. 175,930.

To all whom it may concern:

Be it known that I, JOSEPH E. SCHUMACHER, a citizen of the United States, residing at Los Angeles, in the county of Los Angeles and State of California, have invented new and useful Improvements in Collapsible and Extensible Shelters, of which the following is a specification.

This invention relates to collapsible and extensible shelters, and it has for its object to provide a shelter which may be readily assembled for use or knocked down for storage or transportation and which will have such advantages in use as inherent stability and opaqueness and which, may be constructed of fireproof, heat-insulating and sound-proof materials. Shelters organized in accordance with the invention are useful for military purposes, camping, storage of automobiles, aeroplanes, and the like, and in fact for any purpose for which a weather-proof shelter is required.

In accordance with the invention, a shelter comprising skeleton frame members and inter-engaging panels is provided.

A highly satisfactory material for the side-wall and end wall sections or panels and the roof sections or panels is plaster board which is composed of two surface sheets of paper or the like and an interposed plastic composition which forms a sort of artificial stone, and shelters composed in the main of such plaster board will have all the advantages and qualities above recited, as well as having thin and light walls and therefore occupying but small space when the shelter is in knocked down form and therefore being easily transported. Such plaster board, when properly organized, has great stability and rigidity, these qualities being essential in a shelter of this character.

It will be understood that plaster board of sufficient width and length to permit the forming of each section of a single piece of plaster board is now on the market, methods which permit the making of plaster board in such large units and sufficiently thin being disclosed and claimed in Letters Patent of the United States No. 1,176,322, and Letters Patent of the United States No. 1,176,860, both granted to John Schumacher and myself March 21, 1916, and March 28, 1916, respectively, both for processes of making plaster board.

The invention has for a further object to provide a shelter of the character above

stated which will be relatively simple and inexpensive in construction and organization, when its advantages such as facility in assembling and disassembling, fire-proof qualities, and general superiority in service are considered.

With the above and other objects in view, the invention consists in the novel and useful provision, formation, combination, and association of parts, members and features, all as hereinafter described, shown in the drawings and finally pointed out in claims.

In the drawings:

Fig. 1 is a perspective view showing a plurality of shelter units organized in accordance with the invention and connected together;

Fig. 2 is a transverse sectional view taken on the line x^2-x^2 , Fig. 3, and looking in the direction of the appended arrows, the view being taken upon an enlarged scale;

Fig. 3 is a fragmentary side elevation of the showing in Fig. 1, parts being broken away and sectioned for clearness of illustration, and upon an enlarged scale;

Fig. 4 is a transverse sectional view of a portion of the showing in Fig. 2, the view being taken upon a still further enlarged scale, and illustrating details of construction;

Fig. 5 is a fragmentary front elevation of the improved shelter, details of window construction being illustrated in this figure, and upon an enlarged scale;

Fig. 6 is a vertical sectional view taken on the line x^6-x^6 , Fig. 5, and looking in the direction of the appended arrows;

Fig. 7 is a fragmentary view taken along the line x^7-x^7 , Fig. 5, and looking in the direction of the appended arrows;

Fig. 8 is a fragmentary side elevation of the ridge pole of the shelter upon an enlarged scale;

Fig. 9 is a vertical sectional view of the ridge pole of the shelter, taken on the line x^9-x^9 , Fig. 8;

Fig. 10 is a view, partly in section, of one of the bolt and nut devices employed for assembling the ridge pole;

Fig. 11 is a fragmentary horizontal sectional detail view taken on the line $x^{11}-x^{11}$, Fig. 2, and looking in the direction of the appended arrows, and upon an enlarged scale;

Fig. 12 is a fragmentary horizontal sectional view taken on the line $x^{12}-x^{12}$, Fig.

2, and looking in the direction of the appended arrows, and upon an enlarged scale;

5 Fig. 13 is a fragmentary detail perspective view of corner post and wall construction, the view being taken upon an enlarged scale;

10 Fig. 14 is a perspective view of fragments of the side wall panels of the improved shelter, showing a plurality of units 15 constituting a side wall and the mode of interlocking the same;

15 Fig. 15 is a perspective view of fragments of roof sections of the improved shelter, a plurality of abutting sections being shown;

20 Fig. 16 is a fragmentary inner face view of one of the roof sections, showing a hook whereby the roof section is secured to the ridge pole, the view being upon an enlarged 25 scale; and,

Fig. 17 is an enlarged sectional detail view through a joint, illustrating the preferred manner of joining roof and wall units.

25 Corresponding parts in all the figures are designated by the same reference characters.

Referring with particularity to the drawings, the improved shelter is therein shown as comprising a ridge pole A supported 30 upon uprights a, roof panels B, side panels C, and end panels D.

35 The ridge pole A preferably comprises an upper ridge pole member 18 and a lower ridge pole member 19 joined together by bolts 20 passing through apertures 18^a and 19^a provided at spaced intervals in the ridge pole. The lower ridge pole portion 19 is provided with a longitudinal groove 21 and has inclined upper faces 22, one at each side 40 of the groove or channel 21, upon which faces the roof sections or panels B are adapted to lie. The upper ridge pole member 18 is formed with a central longitudinal tongue 23 at each side of which a downwardly facing inclined face 24 is provided. The tongue 23 has angularly downwardly 45 inclined sides 23^a ranging at right angles to the inclined faces 24. Each bolt 20 is first passed through an inverted U-shaped 50 clip 25 and through the ridge pole member 18, through the aperture 18^a thereof and then extends into and through the aperture 19^a of the lower ridge pole 19. A transverse pin or bolt 26 is passed through a horizontal aperture 27 in the upper ridge pole member 18 and through an aperture 28, in the bolt 20, thus firmly uniting the bolt with the upper ridge pole member 18. At its lower end, each bolt 20 is threaded as at 55 20^a and a thumb nut or the like 20^b is applied thereto, the thumb nut 20^b having a shank portion 29 and a grip portion 30, a circumferential groove 31 being provided in the shank portion 29 and into which a 60 washer 32, which may be split, is fitted. At 65

the terminus of each bolt 20, the lower member 19 is chambered as at 33 to receive the shank 29 of the thumb nut 20^b. The washer 32 is secured to the under side of the lower ridge pole member 19 as by means of screws 70 or the like 34 passed through suitable apertures in the washer 32 and into the ridge pole member 19. At each end of the shelter, and intermediately of the ends thereof, in the double unit shelter illustrated in the 75 drawings, a vertical upright a is provided and such vertical upright comprises, in each instance, a post 35 set into the ground as at 36 at its one end, and provided at its other end with a projecting pin 37 which takes 80 into a suitable aperture in the lower member 19 of the ridge pole A.

At the floor line of the shelter, at each end thereof, and intermediately of the ends thereof at the vertical post 35, a horizontal 85 transverse frame member 38 is provided, such frame member being joined to the respective post 35 as by a bolt and nut device 39, a mortise joint being provided as at 39^a so that the transverse member 38 may be 90 slightly set into its post 35. Near each end of each transverse member 38, a vertical side post 40 is provided and such side post is bolted to the transverse member as at 41 and ranges upwardly therefrom to the top 95 of the side walls of the shelter where, at each side of the shelter, a longitudinal frame member 42 is provided, such frame member 42 resting upon the inclined upper surface of the respective post 40 as at 43, and being bolted thereto as by means of bolts 44 passed through the respective post, the respective longitudinal member, and a roof panel B. Longitudinally ranging base members 45 are provided at each side of the shelter and 100 such members 45 are mortised into the posts 40 as at 45^a and are rabbeted as at 45^b to receive the side panels C, such longitudinally ranging members 45 preferably resting upon the transverse horizontal members 105 38 and being clamped between the posts 40. Other and shorter outer post members 40^b are provided at each corner of the shelter, being secured in position by means of bolts 46 passing through the posts 40, the longitudinally ranging members 45 and the members 40^b. Further inclined transverse members 47 are provided at each end of the shelter, and such members range one at each side of the ridge pole from such ridge pole 110 115 to the respective corner post 40.

The roof of the shelter comprises a plurality of panels B, each preferably composed of a sheet of plaster board 48 and a plurality of longitudinal reinforcing strips 49 nailed 125 or otherwise secured to the sheet of plaster board 48 at predetermined spaced points. At the roof joints or points of inter-engagement of the roof panels B, a reinforcing strip 49^a is provided and such strip slightly overlaps 130

the next adjacent panel as at 49^b, Fig. 15. The edge of such adjacent panel B at the joint at 49^b is preferably reinforced on one side only as at 49^c by means of a strip as of 5 wood or the like secured thereto and the abutting edge of the panel B carrying the respective overlapping reinforcement 49^a is reinforced on its under side by a strip of wood or the like 49^d which abuts against the strip 49^c. A plurality of rotatable buttons or 10 clamps 50 are secured to each of the strips 49^d as by means of screws 51 passed through the clamps 50 and into the respective roof panel B, so that as the roof is being assembled the clamps may be turned to the 15 position shown in Fig. 17 whereby all the roof panels are maintained in a single plane and the joints as between the panels are kept tight. Each of the roof panels is provided at its under side with a transverse reinforcing strip 52, which strip ranges longitudinally of the ridge pole when the panels are in place and at the ends 53^a of the inside longitudinally ranging reinforcing 20 strips 53 provided on the plaster board sheets 48 and in registration with the external strips 49 which range longitudinally of the plaster board sheets 48. At the outer face of each roof section, and at the upper 25 edge thereof the spaces between the reinforcing strips 49 are filled with short strips 54, such strips being nailed or otherwise secured to the sheet of plaster board 48 as are all of the other strips. On the inner face of each 30 roof panel B, and on the strips thereof, a plurality of preferably sheet metal clips 55 are provided and such clips are preferably secured to the respective panel by means of screws or the like 56, each clip being formed 35 with a portion 55^a bent at right angles to the respective panel and forming a hook 40 adapted to take into the channel or groove 21 in the ridge pole member 19 when the shelter is assembled. At the edges of the 45 roof panels which are placed at the ends of the shelter the reinforcing strips 49 and 53 preferably have their outer edges flush with the extreme edge of the sheet of plaster board 48 as no inter-engaging joint is to be 50 made there. On the under side of the roof panels B, a continuous reinforcing strip 56^a is provided and such strip ranges across the respective panel at the ends of the longitudinal reinforcing strips 53. 55 The side walls of the shelter are formed 55 of a plurality of inter-engaging side panels C, such panels C being preferably organized similarly to the roof panels and each being composed of a sheet of plaster board 57 pro- 60 vided with external vertically ranging reinforcing strips 58 of wood or the like, and internal reinforcing strips 59 in registration with the strips 58, all of the strips 58 and 59 being nailed or otherwise secured to the 65 plaster board sheet 57. As the plaster board

sheets may be formed of sufficient width to permit the use of the sheet as a side wall with one of its side edges at the ground line and the other of its side edges at the upper end of the side wall, the strips are preferably 70 placed transversely of such sheet of plaster board so that fewer units are required, due to the greater length in which plaster board may be supplied, for the side walls, than for the roof. At the point of junction of 75 the side wall members C, one of the sheets of plaster board 57 is provided with a reinforcing strip 60 at its outer face, which strip 60 overlies the joint where two plaster board sheets 57 abut. At the inner face of 80 each sheet 57 a reinforcing strip 61 is provided, such strip 61 being flush with the ends of the plaster board units. Buttons or clamps similar to the clamp 50 may be provided on the strip 51 which is nailed to the 85 plaster board sheet 57 to which the joint covering reinforcing strip 60 is applied to maintain the walls in alignment at the joints. Horizontal battens or reinforcing strips 62 are applied to the plaster board sheets 57 at 90 their lower edges and at the lower terminals of the vertical strips 59 and 60.

The end panels D of the shelter are each preferably formed of a sheet of plaster board 64 reinforced as by means of external 95 vertical spaced strips 65 and likewise reinforced by internal vertical strips 66 in registration with the strips 65. Transverse horizontal strips 67 may be secured at the base of each of the end panels at the terminals 100 of the inside reinforcing strips 66. The end panels D may have suitably formed windows or a doorway provided therein, one panel provided with a doorway being shown in Fig. 1, and panels provided with windows 105 being shown in Figs. 1 and 2. The upper edges of the end panels are angularly cut with respect to the sides of the panels so as to fit against roof members as at 68. At the longest edge of one of the end panels at each 110 end of the shelter a strip 69 is provided and such strip is arranged to overlie the next adjacent panel, covering the joint. Windows may be provided as by providing apertures d in the plaster board panels in the 115 end panels and the strips thereon, which strips may be used as guides for window frames 70 and 71, the window frames 70 and 71 being arranged in pairs with the frame 71 interiorly of the shelter and the frame 70 exteriorly of the shelter. The frame 70 is provided with a glass 72 and the frame 71 may be provided with a panel 73 of any suitable material such as screen or opaque material. The window frames 70 and 71 120 being of a width to permit the same being guided by the strips 66 on the inside of the shelter wall and the strips 65 and 69 on the outside of the shelter wall, retaining members 74 are applied to the strips as by nail- 125 130

ing, and such retaining members 74 may comprise short metallic bars which project from the strips to overlie the frames 70 and 71 at the side edges thereof as will be understood by reference to Figs. 1, 2 and 5. The frames 70 and 71 and the orifice *d* are shaped to conform and at the upper portion of each orifice and externally of the shelter, a sheet metal shield 75 may be provided, such shield being shown as of triangular form and having two of its edges 76 and 77 secured or abutting against reinforcing members such as the strip 65 and the member 47, while its free edge is flared outwardly and downwardly as at 78 to overlie the outer window frame 70 when the same is in raised position, thus preventing invasion of the shelter by rain. The window frames 70 and 71 are suspended from a cord 79 passed over pulleys 80 set into an aperture 81 in the member 47, one end of the cord 79 being secured to the window frame 70 as at 79^a and the other end of the cord 79 being secured to the window frame 71 as at 79^b. In one of the panels 25 D a large aperture 82 forming a doorway may be provided, and such doorway may be bounded by reinforcing strips such as the strips 65 and horizontal strips or frame members 83 and 84 disposed respectively at 30 the upper portion of the doorway and the lower portion thereof, and a further frame member 85 adapted to lie against the vertical post 35 and be properly secured thereto. A door 86 may be suitably hinged to the 35 door frame so formed.

In assembling the shelter, the vertical posts 35 are first placed in the ground to the required depth and properly spaced, a convenient way of properly spacing the 40 posts 35 being to use the ridge pole as a measuring stick, the ridge pole being provided with suitable indicating marks to that end. After the posts have been set into the ground, one at each end of the shelter and 45 in such a shelter as shown in Fig. 1 composed of two shelter units, a post 35 is set into the ground between the end posts 35, or more than one such intermediate post may be employed. The ridge pole may then 50 be placed in position on the pins 37 projecting from the posts 35, suitable pin-receiving apertures being provided in the lower member 19 of the ridge pole A. The horizontal transverse members 38 may then be 55 bolted to the posts 35 and the corner or side vertical post 40 then applied to the transverse members 38 near the ends thereof as by means of the bolts 41. After the side posts 40 are in position the longitudinal base members 45 and longitudinal roof supporting members 42 rest upon the inclined upper faces of the posts the member 42 being provided with an angularly related rabbet 42^a. Bolts 44 may be applied to the 60 posts and the respective members 42, such bolts, however, preferably extending also through roof panels. The side wall panels C are applied to the base members 45 as by resting the same in the rabbet 45^b of the base member and bolting such side 70 panels to the post 40 as by means of bolts 40^a. An outer side post 40^b is provided at each of the posts 40 and the same preferably extend to a point at approximately half the height of the posts 40, bolts 40^c 75 being provided through suitable apertures in the posts 40, the side sections C, and the posts 40^b. The side panels may be interengaged at adjacent ends as hereinabove described, as by abutting such suitably 80 formed panel ends and turning buttons or latches organized as are the clamps 50. At such junction of adjacent panels a post 40 may be provided and bolts may extend through the panel if desired, or the panels 85 may be merely latched or clamped together at such point. After the side walls are so positioned the roof panels B may be successively applied as by turning the nut 30 on the bolt 20 of the ridge pole A. The 90 uppermost of the ridge pole members will be raised by the bolt to provide a space wide enough to permit insertion of the hook-carrying ends of the roof panels B. The panels may be hooked into the ridge 95 pole, as indicated in Fig. 9, and the ridge pole members 18 and 19 drawn together by tightening the nut 30 of the screw 20, thus securely uniting the panels with the ridge pole in wedging action. As adjacent panels 100 are applied successively in building up the roof the panels may be caused to abut and the buttons or clamps 50 turned, from the under side of the roof, to maintain adjacent panel edges in alinement. As the panels are 105 so applied to the ridge pole their ends near the eaves of the shelter will lie upon the respective longitudinal member 42, and the bolt 44 may be passed through suitable 110 apertures provided in the panels and wing nuts or the like 44^a applied thereto, thus securing the roof panels in place. The end walls may be applied by setting the same upon the transverse members 38 and at the outer face of the respective post 35 and securing the same as by means of bolts or the like. The transverse members 38 are provided with a raised molding or the like 38^a 115 against which the end panel sections D may abut at their bases. In localities where it 120 is necessary to brace the structure to withstand severe winds or storms, an anchor rod 87 is provided at each post 40 and externally of the shelter, the respective bolt 40^a serving to bolt the eye 87^a provided at 125 one end of the anchor rod to the wall of the structure, and such anchor rod may lie against the extreme end of the respective member 38 as at 38^b and thence pass into the ground to an anchor 38^c. A turn buckle 87^b 130

may be provided in each anchor rod to tighten the same.

In the form of shelter shown as comprising a plurality of units, each with a ridge pole and panels to extend throughout the length of the ridge pole, the ridge poles may be connected as by means of a metal joining member screwed or otherwise secured to adjacent abutting ends of the ridge poles, and further shelter units may be added by leaving off end walls of the intermediate units so that long shelters may be provided in single structures for field hospital purposes and the like. In disassembling the shelter, the nuts on the bolts extending through the roof panels may first be loosened and the roof panels removed one at a time by unhooking the same from the ridge pole, the ridge pole members 18 and 19 having first been separated by rotating the nut 30 of the bolt 20 in the proper direction. The ridge pole or poles may then be lifted off the vertical post, the end panels removed by loosening the nuts on the bolts by means of which such end panels are secured, the anchor rods may be removed by loosening the nuts on the bolts 40^a, and upon loosening of all of the bolts holding the side walls to the longitudinal base members 45 and the posts 40 and releasing the clamps joining such side members panel after panel of the side walls may be removed. All that is then necessary is to remove the ridge pole A from the top of the uprights 35, loosen the bolts joining the posts 40 to the members 38 and the bolts joining the members 38 to the vertical posts or uprights 35 and withdraw the uprights from their position in the ground.

The panels and other members forming the shelter may be stacked or otherwise arranged for transportation, and the knocked-down shelter will occupy but little space.

The shelter may again be re-assembled or erected by proceeding as hereinabove outlined.

Bent iron strips 44^b may be applied to the posts 40 and the longitudinally ranging members 42, the bolts 40^a and 44 passing through suitable apertures in such strips.

Having thus disclosed my invention, I claim and desire to secure by Letters Patent:

1. A portable house including a ridge pole divided longitudinally into complementary sections, roof panels adapted to have the edges thereof clamped between the complementary sections of the ridge pole, bolts

extending through the ridge pole sections and carried by one of the sections, plates secured to the other section, and clamping nuts permanently swiveled upon the plates and engaging the bolts for co-operation therewith to positively move the ridge pole sections toward and away from each other.

2. A portable house including a ridge pole divided longitudinally into complementary sections, roof panels adapted to have the edges thereof clamped between the complementary sections of the ridge pole, clamping bolts extending through the sections of the ridge pole, transverse strips extending around the outer face of one of the ridge pole sections, transverse pins extending through the said ridge pole sections and engaging the ends of the strips and the clamping bolts, plates permanently secured to the other ridge pole section, and nuts swiveled upon the plates and engaging the bolts, said nuts co-operating with the bolts to move the ridge pole sections toward and away from each other.

3. A portable house including a frame, interengaging plaster board panels fitted upon the frame, said plaster board panels being reinforced by strips extending transversely across the same and applied to opposite sides thereof in an opposed relation to each other, the reinforcing strip at one edge of each of the panels overhanging the same at one side thereof so as to overlap an adjacent panel, while on the opposite side of the panel the reinforcing strips abut against each other, and fastening means connecting the abutting reinforcing strips to hold the panels together.

4. A portable house including a frame, interengaging plaster board panels fitted upon the frame, said plaster board panels being reinforced by strips applied to opposite sides thereof, certain of the strips on one side of the panels being arranged to overlap adjacent panels, while certain strips on the opposite side of the panels abut each other at the meeting edges of the panels, and fastening means connecting the abutting strips to lock the panels together.

In testimony whereof, I have signed my name to this specification in the presence of two subscribing witnesses.

JOSEPH E. SCHUMACHER.
